COMBINED ESCAPE APPARATUS AND LINE-BRAKE

Charles A. Clark, 764 N. Madison Ave.,
Los Angeles, Calif. 90029

Filed Aug. 21, 1972, Ser. No. 282,572

Term of patent 14 years

Int. Cl. D2—02

U.S. Cl. D2—27

FIG. 1 is a perspective view of a combined escape apparatus and line brake embodying my new design;

FIG. 2 is an elevational view of the device shown in FIG. 1;

FIG. 3 is an elevational view, similar to FIG. 2, but rotated 90° with respect to FIG. 2;

FIG. 4 is an end view taken from the upper end of the device as represented in FIG. 2;

FIG. 5 is an end view taken from the lower end of the device as illustrated in FIG. 1;

FIG. 6 is a partial side elevational view of an alternative configuration for the bottom end of the brake rod portion of the apparatus; and

FIG. 7 is a partial perspective view showing the harness portion of the apparatus unwound in a condition for use, the brake rod taking the form of the species of FIG. 6.

I claim:

The ornamental design for a combined escape apparatus and line-brake, substantially as shown and described.
